UNITED STATES PATENT OFFICE.

THOMAS KERR, OF LONDON, CANADA, ASSIGNOR TO GEORGE R. KERR, OF LONDON, CANADA, AND WILLIAM W. KERR, OF CHICAGO, ILLINOIS.

RAIL-BOND FOR ELECTRIC RAILWAYS.

SPECIFICATION forming part of Letters Patent No. 722,991, dated March 17, 1903.

Application filed August 5, 1901. Serial No. 70,852. (No model.)

To all whom it may concern:

Be it known that I, THOMAS KERR, a subject of the King of Great Britain, and a resident of the city of London, in the county of 5 Middlesex, in the Province of Ontario, Canada, have invented a new and useful Rail-Bond for Electric Railways, of which the following is a specification.

This invention relates to a device for bonding the rails together electrically, so that the electrical current will pass from one rail to the other; and this invention consists of the improved construction and novel combination of parts, as will be hereinafter first fully set 15 forth and described and then pointed out in the claims.

Reference being had to the accompanying drawings, Figure 1 is a perspective view of my improved electrical bond adjusted in position for electrically bonding the adjacent ends of two rails together. In this view the bolts or other securing devices used to secure the coupling to the rails are not shown. Fig. 2 is a detail perspective view of the electrical bonding-wire. In this view the rails are shown in dotted lines. Fig. 3 is an end view of Fig. 1. In this view the electrical bonding-wire is removed. Fig. 4 is a detail perspective view of the coupling, showing the 25 two sections into which it is divided slightly separated and the upright portion of one section cut away.

In the accompanying drawings the numerals 1 and 2 designate a portion of two rails, the ends of which are adjacent to one another, and *d* designates the flanges, and *e* the webs, of said rails.

The numeral 3 designates the rail-coupling, formed in two sections *a b* and with a base *c*, 40 and in each of the vertical portions of said coupling 3 a recess *f* is formed for the purpose which will be hereinafter set forth.

The numeral 4 designates a groove formed in and extending diagonally across the base *c* of said coupling 3, and said coupling is preferably divided into two sections *a b*, diagonally across said base and in line centrally through the groove 4.

5 designates a bonding-wire preferably 45 formed of copper, which wire rests in the groove 4 in the base *c* of the coupling 3, and

one end of said wire 5 is folded at 5^a over the flange *d* of the rail and inserted in a recess *f* in the coupling 3, and between the latter and the web *e* of the rail and the other end of the 55 bonding-wire 5 is also folded at 5^a over the flange *d* on the opposite side of the adjacent rail and is inserted in a recess *f* in the coupling 3 between the latter and the web *e* of the rail.

In the accompanying drawings, particularly in Fig. 3, clamping-bolts 6 6 are shown securing the coupling 3 to the rails 1 and 2, and about four are usually employed for this purpose; but they may be secured together in 65 any manner or by any means found most suitable or convenient, and elongated bolt-holes (not shown) are preferably formed in the coupling 3 to allow for expansion and contraction.

When placed in proper position, the bonding-wire rests in the groove 4 of the base *c*, and the upright portions of the sections *a b* of the coupling 3 rest against the opposite sides of the ends of the adjacent rails, and the base *c* projects under the ends of the adjacent rails, and when the ends of the bonding-wire are folded and inserted in the recesses *f* the whole is firmly clamped and rigidly secured together by the bolts 6 6 or 80 other suitable securing devices.

When arranged and secured together as described, the bonding-wire 5, which is slightly larger in cross-section than the grooves or recesses 4 and *f*, respectively, and 85 which extends diagonally across the line of the rails, will extend across their abutting ends centrally of the line of rails, and when the clamping-bolts 6 are firmly tightened the effect will be to clamp and tightly bind the 90 coupling 3 and rails 1 and 2 together. This will firmly clamp the ends of the bonding-wire 5 against the webs *e* of the adjacent rails,

and the drawing of the sections *a b* of the coupling together when tightening the clamping-bolts 6 6 will compress the adjacent faces of the sections *a b* of the couplings 3 together at the groove 4. This will firmly clamp and compress the bonding-wire 5 against the under side of the rails, so that the bonding-wire 5 being firmly held against the under side of the ends of the adjacent rails and be-

ing bent around the flanges *d* and the ends firmly held against the webs *e* of the adjacent rails a very efficient electrical bond is provided and one the greater portion of 5 which will be concealed, and thereby very difficult to surreptitiously remove or tamper with them in any way, and one all accidental displacement of which to render the bond ineffective will be avoided and completely 10 prevented.

I have found by experiment that the construction herein shown and described gives the best results. At the same time, while I prefer said construction, I do not wish to 15 limit myself to the details thereof, as they may be modified in various ways without departing from the spirit of my invention. For instance, the end portions of the bonding-wire 5 instead of being folded and clamped 20 between the coupling 3 and web *e* of the rail the ends of said bonding-wire may be firmly held in sockets formed in the rail.

Having thus described my invention, I claim—

25 1. In a device of the class described, an electrical bonding-wire, in combination with, extending diagonally across the line of, and across the adjacent ends of the rails of an electrical railway, and one end of said bonding-wire folded over the flange of and abutting against the web at one side of one of 30 said rails, and the other end of said bonding-wire folded over the flange of and abutting against the web at the opposite side of the 35 adjacent rail, and means for holding the rails together, substantially as and for the purpose set forth.

2. In a device of the class described, an electrical bonding-wire, in combination with, 40 extending diagonally across the line of and across the adjacent ends of the rails of an electrical railway, and a coupling consisting of a base and two upright portions, and divided into two sections by dividing the base diagonally across the line of the rails, a groove 45 formed in the base of said coupling diagonally across the line of said rails, and means for firmly holding them together, substantially as and for the purpose set forth.

3. In a device of the class described, an 50 electrical bonding-wire, in combination with, extending diagonally across the line of, and across the adjacent ends of the rails of an electrical railway, and one end of said bonding-wire folded over the flange of and abutting 55 against the web at one side of one of said rails, and the other end of said bonding-wire folded over the flange of and abutting against the web at the opposite side of the adjacent rail, and a coupling consisting of a 60 base and two upright portions, and divided into two sections by dividing the base diagonally across the line of the rails, a groove formed in the base of said coupling diagonally across the line of the rails, and a re- 65 cess formed in each of the upright portions of said coupling to receive the bonding-wire, substantially as and for the purpose set forth.

In testimony whereof I have signed in the presence of the two undersigned witnesses. 70

THOS. KERR.
